UNITED STATES PATENT OFFICE.

ARTHUR J. WIDMER, OF WEBSTER GROVES, MISSOURI, ASSIGNOR, BY MESNE ASSIGNMENTS, TO WIDMER ENGINEERING COMPANY, OF ST. LOUIS, MISSOURI, A CORPORATION OF MISSOURI.

APPARATUS FOR CONSTRUCTING RIBBED CONCRETE FLOORS.

1,238,858.

Specification of Letters Patent.

Patented Sept. 4, 1917.

Application filed December 1, 1916. Serial No. 134,288.

To all whom it may concern:

Be it known that I, ARTHUR J. WIDMER, a citizen of the United States, and a resident of Webster Groves, in the county of St. Louis and State of Missouri, have invented a new and useful Improvement in Apparatus for Constructing Ribbed Concrete Floors, of which the following is a specification.

10 This invention relates particularly to the centering and forms for the floors of buildings of two or more stories in height, and has for its objects to save lumber in the construction of the centering, and to permit 15 the floor forms to be used repeatedly. Further objects are to arrange the centering for supporting the forms so as to expedite the erection of the centering and forms, and so as to permit easy removal of the forms 20 apart from the centering, which may be left in place until the floor has set sufficiently to support itself and the loads which may come upon it.

The invention consists in arranging the 25 joists for supporting the forms for the ribs and panels in rows extending crosswise of the ribs and spaced about four or more feet apart, the tops of these joists being even with the lower edges of the ribs, and resting 30 the ends of the forms for the ribs and panels upon removable cleats or strips which are detachably secured along the sides of the joists, the gaps over the joists between the ends of the forms being filled 35 with sheet metal shields which rest upon the joists or upon the ends of the forms.

Further objects and details of the invention appear in the following description thereof, reference being had to the accompanying drawings, which show the invention in several forms.

In the drawings, wherein the same reference characters designate the same or similar parts in the several views,

40 Figure 1 is a vertical sectional view of a floor, the section being taken parallel to and between the ribs, the forms for the ribs and panels being shown in elevation at the left hand side of the figure;

Fig. 2 is a top plan view of the forms 50 shown in Fig. 1, showing them partly removed to disclose the centering beneath;

Fig. 3 is a vertical sectional view of the floor shown in Fig. 1, transversely of the ribs, on the line 3-3 in Fig. 1, looking in 55 the direction of the arrows;

Fig. 4 is a similar view taken on the line 4-4 in Fig. 1, looking in the opposite direction to Fig. 3;

Fig. 5 is a view like Fig. 1, showing the 60 centering in place for supporting the floor after the forms for the ribs and panels have been removed;

Fig. 6 is a vertical sectional view of a portion of a floor, the section being taken 65 parallel to and between the ribs, showing a modified form of centering and forms;

Fig. 7 is a transverse vertical sectional view of the same, the section being taken on the line 7-7 in Fig. 6 looking in the direction of the arrows;

Figs. 8, 9, 10 and 11 are transverse vertical sectional views showing various modifications of the forms for the ribs and panels;

Figs. 12 and 13 are sectional views similar to Figs. 6 and 7, respectively, showing another modification of the centering and means for supporting the forms for the ribs and floors;

Figs. 14 and 15 are sectional views similar to Figs. 12 and 13, showing a further modification of the means for supporting the forms for the ribs and floors; and

Figs. 16 and 17 are side views of different hangers for the cross pieces which support the forms for the ribs and floors, showing them in place on the joists.

The type of floor shown in the drawings consists of a thin slab of concrete 20 having parallel ribs 21 on its under side for strengthening it between the points of support, such as the wall 22 and the beam 23. The floor is molded in forms made of wood or metal, which are shaped to conform to 95 the shape of the under side of the floor and ribs, and which are supported on suitable centering.

In the construction shown in Figs. 1 to 5, inclusive, the forms for the beams 23 are wooden troughs consisting of bottom boards 24, side boards 25 and top boards 26, 5 supported on cross pieces 27 which are spiked to posts 28. The posts 28 are arranged in pairs, one post of each pair on each side of the beam, and are spaced far enough away from the sides of the beams 10 to permit the latter to be lined up on the cross pieces 27 without difficulty.

The forms for the floor and ribs consist of soffit boards 29 for supporting the lower edges of the ribs 21, and inverted wooden or 15 metal troughs 30 which have slanting sides and which fit between the ribs and conform to the sides of the ribs and under face of the floor slab. The adjacent ends of the troughs 30 are spaced apart, and metal- 20 shields or hoods 31 are used for covering the gaps between them. At the ends of the ribs 21 the troughs may be closed, or covered by metal hoods 31 having their exposed ends closed by wooden or metal end pieces 32. 25 The troughs 30 and soffit boards 29 are in short lengths of four feet or thereabout, easy to make and to handle, and not easily broken or warped out of shape.

The soffit boards 29 and troughs 30 are 30 supported at their ends on cross pieces or stringers 33 which are detachably secured to joists 34 arranged crosswise of the ribs and supported on rows of intermediate posts 35. The nearest joists to the beam 23 are sup- 35 ported on the tops of the posts 28. The tops of the joists 34 are flush with the tops of the soffit boards 29 so as to support the under sides of the ribs 21. The soffit boards and troughs are cut a trifle shorter than the 40 spaces between the joist 34 to permit them to swell somewhat. The hoods 31 have flanges 36 on the lower edges of their side walls which rest on the joists 34 and fill the gaps between the ends of the soffit boards 45 29. The ends of the end hoods are closed.

The stringers 33 for carrying the ends of the soffit boards and troughs may be supported in any convenient manner for letting them down in advance of the joists 34. In Figs. 1 to 5 they are shown spiked to the joists. In Figs. 6 and 7 they are supported by cleats 37, which cleats are spiked to the posts 35.

The troughs 30 and soffit boards 29 may be 55 constructed in various ways. In Figs. 6 and 7 the construction is entirely of wood, even to wooden fillers 38 for bridging the gaps between the ends of the troughs. Fig. 8 shows troughs made of wood and provided 60 with lateral flanges 39 on their lower edges to take the place of the soffit boards. Fig. 9 shows metal soffit pieces 40 arranged between the troughs. The soffit pieces 40 have

edge flanges 41 for stiffening them, and by varying the width of the flanges 41 the 65 height of the soffit boards above the stringers 33 may be adjusted to suit different depths of ribs 21 without changing the size of the troughs 30.

Fig. 10 shows metal troughs 42, having 70 flanges 43 along their edges for supporting the soffit board 29. Fig. 11 shows similar metal troughs 44, the flanges 45 along the edges of the troughs being wide enough to meet under the middle of the rib 21, thereby 75 dispensing with any soffit board.

Figs. 12 and 13 show another manner of supporting the stringers 33 to permit of their ready removal in advance of taking down the joists 34. The stringers are supported on brackets 46 which straddle the joists 34, and hook under the stringers. The hook ends of the brackets slope upward away from the joists, and blocks 47 hold the stringers 33 at the outer upper ends of 80 the sloping hooks. By knocking out the blocks 47, the stringers can be let down toward the joists and the forms pulled down.

In Figs. 14 and 15, the stringers 33 are supported on wooden brackets 48 which are 85 suspended from the joists 34 by means of hangers 49 consisting of a top plate resting on the joist and two loops 50 pivoted to the top plate one on each side of the joist, the lower end of each loop 50 passing under the 90 outer lower edge of a bracket 48 and resting in a shallow groove therein. By swinging the loops 50 down against the joist 34 the brackets 48 can be readily removed to lower 95 the stringers 33 and forms for the floor in 100 advance of removing the joists 34.

Fig. 16 shows another form of hanger 51 for supporting the stringers 33, having its hook ends sloping downwardly and supporting wedges 52 upon which the stringers rest. 105 The wedges pass through openings in the 110 ends of the brackets and have projections 53 on their inner ends and lips 54 on their outer ends for preventing them becoming separated from the brackets.

Fig. 17 shows a metal stringer 55 of angle shape for supporting the troughs. A wedge 56 is driven between the body portion of the hanger 57 and the vertical leg of the angle 115 stringer to clamp it against the flange 58 at 115 the outer end of the hook portion.

It is evident that other modifications in the details of construction of the centering and forms can be made, and the invention is not restricted to the forms shown and de- 120 scribed.

I claim the following as my invention:

1. In apparatus for constructing ribbed concrete floors, joists extending crosswise of the ribs and with their tops even with the 125 under sides of the ribs to support them, sec-

tions of forms for the ribs and floor arranged between said joists with their ends supported therefrom, the ends of said sections being spaced apart leaving gaps over 5 said joists, and short sections separable from said forms covering said gaps.

2. In apparatus for constructing ribbed concrete floors, joists extending crosswise of the ribs and with their tops even with the 10 under side of the ribs to support them, stringers detachably secured alongside of said joists, sections of forms for the ribs and floor arranged between said joists and supported on said stringers the ends of said 15 forms being spaced apart leaving gaps over said joists, and short sections separable from said forms covering said gaps.

3. Apparatus for constructing ribbed concrete floors comprising a joist extending 20 crosswise of the ribs, the top of the joist supporting the under sides of the ribs, forms arranged on each side of the joist at right angles, thereto and projecting above, the joist between the ribs, said forms being 25 spaced apart at their ends with the joist between them, and shields arranged over the joist and forming continuations of the forms across the spaces between their ends.

4. Apparatus for constructing ribbed-concrete floors comprising a joist extending crosswise beneath the ribs, the top of the joist supporting the under sides of the ribs, floor forms arranged on each side of the joist and projecting above the joist between the 35 ribs, said floor forms being spaced apart at their ends with the joist between them, soffit boards arranged beneath the ribs and spaced from the joist at their ends, and shields arranged over the joist and forming 40 continuations of the floor forms across the spaces between their ends, said shields having portions underlying the bottoms of the ribs and resting upon the top of the joist for bridging the spaces between the ends of 45 the soffit boards.

5. Apparatus for constructing ribbed concrete floors comprising a joist extending crosswise of the ribs, the top of the joist supporting the under sides of the ribs, floor 50 forms arranged on each side of the joist and projecting above the joist between the ribs, stringers for supporting the ends of said floor forms, and means for removably securing said stringers to said joist, said 55 means being arranged over the joists in the spaces between the ribs.

6. Apparatus for constructing ribbed concrete floors comprising lengths of forms arranged in succession between the ribs with 60 gaps between the ends of successive forms, stringers extending transversely of the ribs at said gaps, said forms being supported on said transverse stringers, and shields ar-

ranged over the stringers and forming continuations of the forms across said gaps. 65

7. Apparatus for constructing ribbed concrete floors comprising a joist extending crosswise of the ribs, the top of the joist supporting the under sides of the ribs, floor forms arranged on each side of the joist and 70 projecting above the joist between the ribs, said floor forms being spaced apart at their ends with the joist between them, the adjacent ends of said floor forms being open, and hangers straddling on said joist between 75 the ribs for supporting said floor forms.

8. Apparatus for constructing ribbed concrete floors comprising a joist extending crosswise of the ribs, the top of the joist supporting the under sides of the ribs, 80 floor forms arranged on each side of the joist and projecting above the joist between the ribs, said floor forms being spaced apart at their ends with the joist between them, the ends of said floor forms being 85 spaced from said joist, and hangers straddling said joist between the ribs for supporting said floor forms, said hangers being arranged to permit said floor forms to be lowered without removing said joist. 90

9. Apparatus for constructing ribbed concrete floors comprising a joist extending crosswise of the ribs, the top of the joist supporting the under sides of the ribs, floor forms projecting above the joist between 95 the ribs, the ends of said floor forms being clear of said joist, and hangers on said joist, said hangers carrying supports for said floor forms arranged to permit said floor forms to be lowered without removing 100 said joist.

10. Apparatus for constructing ribbed concrete floors comprising a continuous supporting member extending crosswise of the ribs beneath their under sides for supporting them, floor forms projecting above said supporting member and having portions extending between the ribs, the ends of said 105 floor forms being spaced apart to clear the sides of said supporting member, means arranged over said supporting member across the spaces between the ends of said forms for supporting the portion of the floor over the supporting member, and means carried by said supporting member for supporting said floor forms, said means for supporting the forms being arranged for removal independently of said supporting member to permit the forms to be lowered without disturbing the supporting member. 110

11. Apparatus for constructing ribbed concrete floors comprising forms for the ribs arranged in sections in longitudinal alignment with gaps between the ends of alining sections, transverse supports for said ribs arranged beneath them at said gaps, means at 115 120 125

the ends of said sections whereby they are held up by said transverse supports, and shields arranged over the supports and bridging said gaps.

5 12. Apparatus for constructing ribbed concrete floors comprising joists extending crosswise of the ribs for supporting them at intervals, sectional forms supporting the floor between the joists, said sectional forms

having their ends free of the joists, and supports for said forms, said supports being supported on said joists in the spaces between the ribs and being removable to permit the lowering of said sectional forms independently of said joists. ¹⁰

Signed at St. Louis, Missouri, this 29th day of November, 1916. ¹⁵

ARTHUR J. WIDMER.
